FRED A. CUFF AND MAURICE H. KEATING, OF MINNEAPOLIS, MINNESOTA, ASSIGNEES TO
H. D. HUDSON MANUFACTURING COMPANY, OF MINNEAPOLIS, MINNESOTA, A COR-
PORATION OF MINNESOTA

SPRAYER

Application filed October 8, 1928. Serial No. 311,139.

This invention relates generally to improvements in sprayers and has, among its features: the utilization of the spray head of the pump cylinder as a means for attaching, 5 and facilitating proper placement of the liquid supply tube, and as means for defining a drip chamber between the head and the end of the cylinder; the placement and the back-spacing or slanting of a portion of the head 10 below the spray orifice so that a straight oil supply tube attached thereto will be related to the supply tank substantially diametrically and will allow the use of the shortest tube possible; and the combined functions of the 15 head, for the above purposes.

The objects, advantages and features of the invention will be set forth in the description of the drawings forming a part of this application, and in said drawings,

20 Fig. 1 is a side elevation partly in section showing one application of the invention to a tank;

Fig. 2 is an end elevation of Fig. 1 viewing the discharge end of the cylinder;

25 Fig. 3 is a side elevation partly in section showing a modification in which the delivery end of the cylinder does not project beyond the tank;

Fig. 4 is an end elevation viewing the 30 discharge end;

Fig. 5 is a section showing a modification in which the cylinder is provided with a slanting plane surfaced end wall;

35 Fig. 6 is a section showing a modification in which the delivery end wall of the cylinder is conical;

Fig. 7 is a section showing a modification in which a portion of the end surface of the cylinder abuts and projects within the supply 40 tank;

Fig. 8 is a section showing a modification in which the end wall of the cylinder is at the extreme end of the cylinder and in which the end wall is bent inwardly to provide a drain 45 chamber.

Numeral 1 indicates a pump cylinder and 50 2, the tank. The cylinder has the usual piston 3 and rod 4 for operating it. The tank is cut out and the cylinder is set in the tank in tangent relation thereto with its extremity

projecting beyond the tank so that the dripping spray will not be deposited upon the tank. There is, however, no intention to be limited to the particular manner in which the cylinder is attached to the tank. Nevertheless the intention is to claim all details of construction of all forms of the invention, along with the broader features. The axes of tank and cylinder are ordinarily substantially perpendicularly related. 55

The orificed end wall of the cylinder, lies at some point inwardly from the extremity of the cylinder, or some portion of the end wall is thus positioned. The wall is indicated at 10 and may be considered, a partition. This inward spacing is for the purpose of defining and providing a drain-chamber generally indicated at 11, disposed between the wall and the open end of the cylinder, thus utilizing a portion of the cylinder for a catch-chamber. This wall is orificed as at 15. Compressed air is forced through the orifice by inward movement of the piston 3, to create a suction action in a liquid supply tube, to be described. 60

A plate 20 functions to complete the catch-chamber and prevent outward flow of any liquid over the lower edge of the end of the cylinder. There is no intention to be limited to this construction which partly closes the end of the cylinder, or to its manner of attachment, but, it will be understood that some means must be employed to prevent egress of residual spray liquid, from the catch-chamber. It is conceivable that the end of the cylinder could be formed in a manner to accomplish this object. In order that liquid may drain into the tank 2, a drain passage 21 is provided, in this instance having the form of an opening in the cylinder. This passage is located adjacent and at the outer side of the wall 10 at that portion of the cylinder, nearest the tank. The details of construction shown are also claimed. 65

The oil tube is indicated at 22 and, in this instance, passes loosely through the drain passage 21 so that its draining function may not be destroyed, and has its upper end arranged in operative relation to the orifice 15. It will be understood that as the air passes 70

forcibly through the opening 15, liquid will be entrained upwardly through the tube 22.

A feature of the invention includes the slanting arrangement of the oil tube and its substantially linear form, the objects being to obtain a tube of minimum length, thus reducing friction as well as the length of travel of the liquid, to generally improve the efficiency of the device and somewhat reduce the cost of manufacture. In order to facilitate assembly and provide a convenient attaching point for the tube, so that it may be secured in slanting relation substantially as shown, and so that its intake end may lie adjacent the bottom portion of the tank wall, and rearwardly of a diameter B drawn through the axis of the tank substantially perpendicular to the cylinder axis, a portion 25 of the wall 10 is bent rearwardly as shown. It will be understood that this arrangement of the tube assures the submergence of the intake end of the tube in the liquid, when the cylinder is pointed upwardly or downwardly, even though the liquid be nearly exhausted. The tube may be attached in any preferred manner to lie substantially in parallel relation, in this instance, to the outer surface of the angular wall portion. The tube may be connected by soldering. The wall 10, see Fig. 5 or the slanting portion 25, see Fig. 1, thus provides a support, as well as a gauge determining the proper angular position of the tube in relation to the tank.

It will be noted that when the sprayer is resting upon a plane surface indicated by dotted line C, the cylinder will assume an angle to facilitate the draining action through the passage 21, which under these conditions will be at the lowest part of the catch-chamber.

By slanting the wall as at 25, the tube can not only be materially shortened, but the liquid is delivered at the spraying point, more nearly, in direction of spray, and thus additional efficiency is secured.

In the modification of Figure 3, the wall 30 and its angular portion 31 bear substantially the same relation to the outer open end of the cylinder as in the first form. However in this form the extremity of the cylinder does not project beyond the tank 2, but meets its curved wall substantially in the manner shown. The element 32 is attached substantially in the manner of the element 20 and it will be noted by inspections of Figures 2 and 4 that this element is the form of a circular segment completing the outer wall of the catch-chamber 11. It is conceivable that an extension of the tank may serve the purpose of the element 32.

In the form of the invention shown in Figure 5 the end wall or plate 35 is elliptical in outline and has a plain surface throughout its entire area. This is a simple construc-

tion because no bending of the plate is necessary, as in the case of the form shown in Figure 3.

In the form shown in Figure 6, the end wall or plate 39 is conical, which has the advantage of converging the compressed air toward the discharge orifice 40. In all forms of the invention that end wall of the cylinder which contains the spray orifice, is arranged to provide a catch-chamber between the end of the wall and the end of the cylinder, with a passage establishing communication between this pocket and the tank, so that leakage at a point outside of the cylinder or beyond the wall in direction of spray, is returned to the supply tank.

The form of the invention shown in Figure 7 is substantially similar to that shown in Figure 3, with the exception that the lower outer end of the cylinder projects slightly into the tank. In this form the wall element 50 is shown as a separate piece connected across the outer end of the cylinder, but there is no intention to be limited to this specific construction, inasmuch as the portion of the wall of the tank may be bent downwardly to form this guard, just as this wall may be bent upwardly to produce the guard or wall of the drain chamber as shown in Figures 3, 5 and 6.

In that embodiment of the invention shown in Figure 8, a portion of the end wall of the cylinder is co-planar with the end of the cylinder, and the lower portion of this wall is bent inwardly as at 60 generally in the manner shown for those forms of the invention illustrated in Figures 1, 3 and 7, to provide the catch-chamber 61.

In all instances the tubes extend loosely through a passage in the wall of the cylinder, which passage establishes communication between the drain chamber and the tank. This is a valuable feature of the invention, as are those features which permit shortening of the tube, and aid delivery generally in the direction of spray, and which provide a drain chamber by arranging and forming the end wall of the cylinder substantially in the manners set forth.

We claim as our invention:

1. A tank and a pump cylinder secured thereto with a portion of the pump cylinder including its end extending into the tank, said tank having a lip partially capping the end of said cylinder, and said cylinder having an end wall spaced from said capping element to form therewith a catch-chamber.

2. A supply tank and a pump cylinder secured thereto, said cylinder having a head having a discharge orifice and a portion below the orifice slanted inwardly away from the end of the cylinder to define a drip chamber between the head and the end of the cylinder, said portion being slanted toward the interior of the tank to form a tube attach-

ment means, a straight tube attached to said slanted portion and passing through the cylinder into the tank, and having one end associated with the discharge orifice so that air forced through said orifice will create suction in the tube, and means closing the end of the cylinder to form one wall of the drip chamber, the top of said means being at a level below the discharge orifice.

3. A supply tank and a pump cylinder secured in tangent relation thereto, said cylinder having a head, that portion of the head which is below the axis of the cylinder being flat and being slanted rearwardly from the end of the cylinder and downwardly toward the interior of the tank, a straight tube attached to said slanted portion and passing through the cylinder into the tank, and having one end associated with the discharge orifice so that air forced through said orifice will create suction in the tube, and the flat portion of the head being so disposed and slanted that the straight tube is disposed in substantially diametric relation to the tank axis and so that it crosses a line drawn through the tank axis perpendicular to the axis of the pump cylinder.

4. A supply tank having a pump cylinder secured thereto in substantially tangential relation, said cylinder having an end wall adjacent the tank, and said wall having a discharge orifice, and said end wall having that portion which is below the orifice flattened and slanted downwardly and inwardly toward the tank, making an angle of substantially sixty degrees with the cylinder axis and so disposed that an extension of its plane surface is substantially diametrically related to the tank axis, and a straight tube attached to said slanted portion and passing into the tank, said tube having one end associated with the discharge orifice so that air forced through said orifice will create suction in the tube.

5. A supply tank having a pump cylinder secured thereto in substantially tangential relation, said cylinder having an end wall adjacent the tank but forwardly of a line cutting the tank axis and perpendicular to the cylinder axis, and said wall having a discharge orifice, that portion of the end wall which is below the orifice being flattened and slanted downwardly and inwardly toward the tank making an angle of substantially sixty degrees with the cylinder axis and so disposed that an extension of its plane surface is substantially diametrically related to the tank axis, and a straight tube attached to said slanted portion passing only through the cylinder into the tank, substantially in diametric relation to the tank axis, said tube having one end associated with the discharge orifice so that air forced through said orifice will create suction in the tube, and so that

the liquid issues in a direction more nearly parallel with the cylinder axis.

In witness whereof, I have hereunto set my hand this 3rd day of Oct., 1928.

FRED A. CUFF. 70

In witness whereof, I have hereunto set my hand this 18th day of September, 1928.

MAURICE H. KEATING.
